DESIGN FOR A LOCKET RING

William Silverman, Providence, R. I.

Application December 30, 1939, Serial No. 89,238

Term of patent 7 years

To all whom it may concern:

Be it known that William Silverman, a citizen of the United States residing at Providence, in the county of Providence and State of Rhode Island, has invented a new, original, and ornamental Design for a Locket Ring, of which the following is a specification, reference being had to the accompanying drawing, forming part thereof:

In the drawing:

Fig. 1 is a front view of a locket ring embodying my new design;

Fig. 2 is a top view thereof showing the locket construction;

Fig. 3 is a side view of the same; and

Fig. 4 is a perspective view of the ring, the locket portion being in open position.

I claim:

The ornamental design for a locket ring, substantially as shown and described.

WILLIAM SILVERMAN.
